UNITED STATES PATENT OFFICE.

BARCLAY ARNEY JAMES, OF EVANSVILLE, INDIANA.

SAFETY-POCKET.

SPECIFICATION forming part of Letters Patent No. 722,584, dated March 10, 1903

Application filed October 30, 1902. Serial No. 129,445. (No model.)

To all whom it may concern:

Be it known that I, BARCLAY ARNEY JAMES, residing at Evansville, in the county of Vanderburg and State of Indiana, have invented 5 certain new and useful Improvements in Safety-Pockets, of which the following is a specification.

My invention relates to wearing-apparel pockets; and the invention consists of a peculiar safety-pocket more particularly intended for drawers, but adapted and is useful in connection with any article of clothing in which such a pocket may be desired.

In order to enable others to make and use 15 my invention, I will now proceed to describe its construction and use with reference to the accompanying drawings, forming a part of this specification.

In the drawings, Figure 1 is a view showing 20 the rear of a pair of drawers with my safety-pockets located at the right-hip side thereof. Fig. 2 is a transverse sectional view taken on line $x-x$, Fig. 1; and Fig. 3 is a detail view showing my special shield.

25 This invention in its broad conception involves providing drawers with a pocket having special means adapted to provide security to the pocket's contents.

More specifically stated, the invention involves 30 a double pocket, in the outer end of which I place a pervious shield of wire-gauze. The outermost layer of the pocket is elongated, forming a free flap adapted to be turned down between the wire-gauze shield and the 35 outer layer of the inner pocket, the latter constituting the pocket to be protected. Safety against dislodgment of the pocket's contents is afforded by an upper flap depending from a point over the pocket. This flap is made 40 adapted to receive a similar shield and when turned down to normal position over the pocket's mouth may be secured by any suitable means adapted for the purpose. The object of the shield just mentioned is to prevent 45 the pocket being cut from the outside and its contents removed. The above statement of the broad features of my invention in connection with the following detail description thereof will render it fully understood.

50 In carrying out my invention I employ two layers of goods, an outer layer A and an inner layer B. These layers are secured to the

drawers by a line of stitching down both sides and along the bottom edge, as shown in Fig. 1. The layers A and B being secured as 55 stated, it is apparent that two pockets C and D will be formed. The outer layer is formed or provided with a free extension or flap E, adapted to be turned down into the pocket C.

F indicates a pervious guard or shield 60 formed of aluminium wire-gauze, having a sheet-metal or other material protecting edge G. This guard is made conforming to the shape of and adapted to be received by the pocket C and when in place is secured there- 65 in by turning down the flap E to position shown in Fig. 2 between it and the inner layer B.

H indicates a flap adapted to extend down, covering part or the whole outer surface of 70 the pocket, and is secured by a socket-fastening of well-known design or by other suitable means. This flap is secured to the drawers by a line of stitching just above the pocket and has an inner layer I secured thereto by 75 stitching along two sides and the free end thereof forming a pocket J, in which is placed a shield K, similar to the shield F. The inner layer I of the flap H is provided with a free extension L, adapted to be turned into 80 the pocket J of the said flap, inclosing its shield, and thereby securing it in place.

While I have shown and described an inner layer B, I do not desire to be limited thereto, since the same may be dispensed with without 85 departing from the spirit of my invention.

So far as I am informed, I think it is original with me, first, to provide drawers with a safety-pocket, and, second, to construct a pocket substantially as hereinbefore de- 90 scribed and employ therewith a shield of the character stated.

While I have shown my special safety-pocket located on the rear of the drawers at its right-hip portion, obviously the same may 95 be placed at any desired location and several of them used, as may be desired.

Having thus fully described my invention, what I claim as new, and desire to secure by Letters Patent, is—

1. A safety-pocket consisting of inner and outer layers, a pervious shield conforming to the shape of the pocket and adapted to be placed therein, and a flap extending from one

of the said layers adapted to be turned down into the pocket inclosing the said shield substantially as described.

2. A safety-pocket and in combination, inner and outer layers and an intermediate layer, a wire-gauze shield conforming to the shape of the pocket and adapted to be placed therein, and a flap secured to the outermost layer adapted to be turned down into the pocket inclosing the said shield substantially as described.

3. In combination with a safety-pocket having a flap adapted to be turned down in the pocket, a previous shield substantially as described.

4. In combination with a safety-pocket having a flap adapted to be turned down in the pocket, a shield conforming to the shape of the pocket and adapted to be secured by the said flap substantially as described.

5. The combination in a safety-pocket, a

flap extending from the outer edge of the pocket and adapted to be turned down therein, a removable shield conforming to the shape of the pocket and adapted to be secured by 25 said flap, an upper flap depending from a point above the pocket-opening and extending down on the outside of the pocket, a shield within the upper flap, and means adapted to secure the said upper flap to closed position 30 over the pocket-opening substantially as described.

6. In combination with a safety-pocket having a flap adapted to be turned down in the pocket, a wire-gauze shield having protected 35 edges and adapted to be arranged in the pocket and be secured therein by the said flap substantially as described.

BARCLAY ARNEY JAMES.
